UNITED STATES PATENT OFFICE.

ARTHUR W. BROWNE, OF PLEASANT PLAINS, N. Y., ASSIGNOR TO THE S. S.
WHITE DENTAL MANUFACTURING COMPANY, OF PHILADELPHIA, PA.

DENTAL-ENGINE HAND-PIECE.

SPECIFICATION forming part of Letters Patent No. 291,571, dated January 8, 1884

Application filed October 31, 1883. (No model.)

To all whom it may concern:

Be it known that I, ARTHUR W. BROWNE, of the village of Pleasant Plains, in the county of Richmond and State of New York, have invented certain new and useful Improvements 5 in Hand-Pieces for Dental Engines, of which the following is a specification.

My invention relates to hand-pieces or tool-carriers for dental and other similar engines, 10 and more particularly to hand-pieces generally known as "chuck" hand-pieces. The tools, bits, or burrs generally used with dental-engine hand-pieces are almost if not quite universally provided with round or cylindrical 15 shanks, and these shanks are generally of about the same diameter. Each manufacturer, however, provides his tool-shanks with a peculiar form of locking-notch adapted to be engaged by the peculiar locking devices carried by the rotary spindle of the hand-piece 20 of his own manufacture. Consequently, when the dentist desires to change his hand-piece from the make of one manufacturer to that of another, his bits or tools are rendered useless 25 until altered to suit the peculiar form of tool-lock in the new hand-piece. The chuck form of hand-piece is intended to receive the shanks of the dental tools without respect to any peculiar formation of the locking-notch therein, 30 so that the hand-piece will drive the tools of one maker as well as those of another.

Several different forms of chuck hand-pieces have already been devised and patented, and some of them possess decided merit; but, as 35 far as I am aware, there had not been produced prior to my invention a chuck hand-piece of simple construction, capable of rapid and easy operation in locking or disengaging a tool, and one in which the tool would be accurately centered and firmly locked against 40 all danger of accidental release when in operation, and in which the steady rotation of the spindle was insured and compensation afforded by rapid and easy adjustment for any 45 wear of the parts.

The object of my invention may be said to be to furnish a superior chuck hand-piece meeting all the requirements demanded in practice of such a device.

50 The subject-matter claimed is particularly pointed out at the close of the specification.

In the accompanying drawings I have shown all of my improvements as embodied in one hand-piece in the best way now known to me.

In said drawings, Figure 1 is a longitudinal central section through my improved hand-piece, showing a tool as inserted therein, but not locked in the socket of the rotary spindle which carries it; and Fig. 2 is a similar view, with the parts in position to lock the tool-shank in said rotary spindle. Fig. 3 is a cross-section through the hand-piece on the line 3 3 of Fig. 1. Fig. 4 is an end and side elevation of one section of the clamping or locking device. Fig. 5 is a detail view, showing the 65 manner of fitting the driving-shaft to which the power-conveyer is connected in the hollow spindle of the hand-piece casing; and Fig. 6 is a section on the line 6 6 of Fig. 5. Fig. 7 is a similar section to that of Fig. 2 of a modified form embodying my improvements.

The tubular casing of the hand-piece is composed in this example of a handle-section, A, a union-section, B, a telescoping or sliding section, C, a screw-threaded section, D, and a 75 swivel or shank section, E, which latter is connected with the usual flexible sheath or covering of the flexible power-conveyer usually employed in dental engines. By means of this swivel or shank section the casing of 80 the hand-piece is free to turn to conform to the turning movements of the hand of the operator. I have not shown in the accompanying drawings said flexible sheath, nor have I deemed it necessary to show the power-conveyer, usually a flexible driving-shaft, as these 85 instrumentalities constitute no part of my present improvements, which are confined to the hand-piece of the engine.

The handle-section A of the casing is united 90 to the union-section B thereof by being slipped upon the reduced front end of said union-section, and is locked thereon by a set-screw, a, having a curved, tapered, or cone end, a', to act against the inclined wall b of a recess in 95 said union-section. The extent to which the handle-section is slipped endwise on the union-section is determined by an adjustable screw, b', fitted in the rear end of the said handle-section of the casing, as clearly shown 100 in Figs. 1, 2, and 7. By adjusting this screw b' so that its head is extended beyond the rear

end of the handle-section of the casing, said screw abuts against the front face of an annular shoulder, b^2 , of the union-section of the casing, and consequently the extent of project-
ure of said screw determines the extent to
which the handle-section of the casing is passed
or slipped upon said union-section thereof. I
prefer the face of said annular shoulder b^2 of
the union-section to have a recess to receive
the head or end of the adjusting-screw b' , as
by this means the proper relation of the two
sections is insured, and the fastening-screw a
always brought in proper position to act upon
the inclined wall of said union-section. It is
obvious that by tightening the screw a the
tendency is to wedge the handle-section back
upon the union-section and lock the two sections
firmly together. I do not claim this ad-
justing-screw and the wedging-screw devices
or connections, however, as they are not of
my sole invention, and are claimed by me
jointly with others in another application.

The union-section B is fitted to receive the
front reduced tubular end of the telescoping
casing-section C, said telescoping section be-
ing provided with a longitudinal groove, c , to
receive a spline or feather, b^4 , of the union-
section B. By this construction the union-
section and telescoping section may be freely
telescoped or slid endwise relatively to each
other, while, when the spline and groove are
employed, they cannot turn independently.
This telescoping construction of the casing
sections is important, as will appear herein-
after in the operation of the tool-locking
devices.

A driving-shaft, F, is fitted to revolve on
its longitudinal axis in the telescoping section
C, and is locked therein, as against endwise
movement, by means of a collar, f , fastened
on said shaft by a through-pin, f' , and em-
braced between an annular internal shoulder
of the telescoping section and the front annular
end of the screw-section D of the casing,
whereby it will be obvious that as the tele-
scopic section is moved in and out of the union-
section the shaft F will be moved endwise there-
with. I prefer to fit hardened-steel washers
or rings f^3 f^2 , one on each side of said collar f ,
for accurate fitting, and to withstand the wear
to which the parts are subjected. The rear
end of said driving-shaft F is connected with
the front end of the power-conveyer—usually
a flexible shaft—as before stated. The front
end of the driving-shaft F is connected with or
carries a rod, G, the shaft and rod being rigidly
connected as against torsional strains,
while loosely connected as against lateral move-
ment or play, the object of which connection
will be presently explained. Said rod G is
fitted to move endwise in the rear end of the
tubular rotary spindle H of the hand-piece, and
said rod drives or rotates said rotary spindle
H, said rod having a feather or lug, g , fitting
a longitudinal slot, h , in the tubular spindle
H, whereby it will be evident that the rod G
is free to be moved in and out of the hollow

spindle, while any turning movements im-
parted to said rod G by the driving-shaft F
will also be imparted to the spindle H. The 70
rear end of said hollow spindle H terminates
in a flat or square annular face, which bears
against the front face of a hard-metal washer,
 i , preferably acting as a facing and guard to a
similar hard-metal washer or plug, i' , fitted by 75
screw-threads in the present example in the
front end of the union-section B of the casing.
By this means the rear end of the hollow spin-
dle may be nicely fitted to bear against the 80
front end of the union-section of the casing
without danger of wear to said section, the
wear taking place against the loose washer i
above described. When said washer is worn,
it may be readily removed and a new one in-
serted in its place. The front end of the hol-
low spindle is cone journaled or tapered to fit
a correspondingly-tapered bearing in the front
end of the handle-section of the casing. It
will be seen that the taper given to the front
end of the hollow spindle is a double taper— 90
that is, the taper for a portion of its length is
at one angle, while for the remainder of its
length, at the extreme front end of the spin-
dle, the taper is at a greater angle. This dif-
ference of taper, or, rather, the provision of two 95
tapering surfaces on different angles, is for the
purpose of resisting side or lateral wear by
means of the slightly-tapered surface h' , and
of preventing the first taper, h' , from wedg-
ing or sticking by means of the taper h^2 at a 100
greater angle at the front end of the spindle.
It will thus be seen that the spindle is nicely
fitted to revolve on its longitudinal axis, and
it will also be observed that any wear of the
journals of the spindle or of their bearings may 105
be readily compensated for by adjusting the
handle-section upon the union-section of the
casing in the manner before fully described.

In the drawings I have shown the hollow
spindle H as having a bearing throughout its 110
entire length in the casing, but in practice the
spindle will be fitted to turn in front and rear
bearings only, with a greater portion of its
sides removed from contact with the interior
of the casing. The rear bearing may be at or
near the rear end of the spindle, and formed
by a hard-metal ring fastened to the inside of 115
the casing, while the front bearing is formed
by a hard metal nose of the handle-section fit-
ted with a tapered bore to receive the tapered
or cone journaled front end of the spindle.
The hollow spindle H, it will be noticed, is en-
tirely inclosed within the casing, so as to avoid
any danger of contact with rotary parts in the
manipulation of the hand-piece; and this spin-
dle in turn contains the tool-locking devices 120
by which the tools to be driven and operated
may be locked in said rotary spindle, the front
end of which constitutes a socket to receive
the shanks of the operating-tools. The bore 125
of the spindle H, at the front end, is tapered
or contracted to receive the tapered or coned
front end of a split-clamp or spring-jawed lock-
ing device. This split clamp or spring-jawed

tool-locking device is composed in this instance of two tubular sections, J J'. The front end, *j*, of the front section, J, is tapered to fit the tapered or contracted mouth of the tool-socket, 5 and the bore or socket at the rear end of said section J is enlarged or flared to receive the front tapered or cone end of the second section J' of the tool-locking device, the front ends of these sections J J' being capable of being 10 compressed by being longitudinally slotted for nearly the whole length of the sections in a well-known way in forming spring-jawed clamps in this class of devices. The rear end of the section J' of the clamp-lock is square or 15 flat, and the front face of a headed pin, K, is nicely fitted to said rear end of the section J', the shank *k* of the pin K being fitted in the rear end of the tool-receiving socket of said 20 spring-jawed clamp-lock.

25 It will be obvious that when no pressure is applied from the rear or upon the head of the pin K the tendency of the spring-jaws of the sectional clamp will be to spread apart and expand, thus opening the tool-receiving socket through them to its full extent. A cylindrical 30 tool-shank of the proper size can now be readily inserted in the spindle. Upon applying pressure upon the rear end of the spring-clamp lock or upon the pin K the front cone end of the section J' of the clamp-lock will be forced 35 into the tapered mouth of the front section, J, and the members or jaws of said section J' will thus be compressed or forced together, while at the same time the front end of the 40 section J will be forced forward and its front spring-jawed end will also be compressed and its members forced together, thereby securely grasping the tool-shank at different points, while the clamp-jaw lock will also be tightly 45 wedged and locked in the rotary spindle, so that the tool-shank will be locked to the spindle, so as to be virtually a rigid portion thereof.

In order to readily apply the desired pressure to operate or compress the spring-jawed 50 clamp, and to enable its members to expand or release themselves when the pressure is released, I apply the pressure through the instrumentality of a pivoted bell-crank lever, L, and operate said lever simply by moving the 55 rod G backward and forward, due to moving the union-section B and telescoping section C of the hand-piece relatively to each other. Said operating-lever L is pivoted by its short arm *l* in the spindle, while the long arm *l'* of said lever extends lengthwise of the spindle, and is fitted to work laterally relatively to 60 said spindle, and in a longitudinal slot, *h*', thereof. The extreme end of the long arm *l'* of the lever *l* is bent, as clearly shown in the 65 drawings, and is adapted to engage a wedge or inclined surface, *g*, formed on or in the endwise movable rod G, before described. Said wedge or inclined surface *g'* of the rod G is preferably roughened or serrated, as clearly 70 shown, in order to form locking-points for the engagement of the end of the lever L.

The operation of the device is as follows:

When the parts are in the position as shown in Fig. 1, the telescoping sections of the casing are in their closed position, the rod G is thrust forward in the spindle, there is no action by the wedge or inclined surface of said rod upon the lever L, and the spring-jaws of the tool-clamp lock are released from pressure, and are separated, so as to readily receive the 75 shank of a tool. The tool to be used in operation is now inserted. The handle-section of the casing is now grasped in one hand and the telescoping section C in the other, and the two separated or pulled apart, as shown in 80 Fig. 2. This separation of the section C from the sections A and B carries the spindle forward, and causes the end of the long arm of the lever L to ride upon the wedging or inclined surface of the rod G, which action, as 85 will be obvious from Fig. 2, causes the elbow of the lever L—at the point *l'*, for instance—to bear against the head of the pin K and force it forward, carrying with it, of course, the spring-clamp locking device, whose ends or 90 jaws are thereby contracted or compressed upon the tool-shank in the manner before explained. The tool may now be directed to its work, and will be firmly, steadily, and securely driven without any danger whatever of the 95 release of the tool, as the force of compression exerted by the spring-jaws, due to the action of the lever L, is comparatively great, and much more efficient than any previous tool-locking device of its kind as far as I am aware. 100 The lever L will be securely held in its locking position by the engagement of its end with one of the teeth or serrations in the wedging, camming, or inclined surface of the rod G. All that is necessary, therefore, it will be obvious, to lock or release a tool, is to move one 105 section of the casing endwise upon the other. The movement may be accomplished instantly, and is easily accomplished without the exercise of much exertion.

110 For the purpose of adjustment and to secure accurate fitting, I prefer to interpose between the head of the pin K and the rear end of the section J' of the spring-clamp lock two or more thin rings or washers, *h*', as is shown in Figs. 1 115 and 2. A ready adjustment may thus be readily effected to secure proper operation of the tool-lock. It will be understood, however, that this adjustment may be accomplished in any other desired manner. For instance, the 120 shank of the pin K might be screw-threaded, so as to be moved in and out.

125 Instead of a sectional or two-part spring-clamp, it may be formed in one piece—for instance, having spring-jaws at its opposite ends beveled or tapered and adapted to be compressed at one end by a proper surface in the spindle, and at the other end by a tapered mouth or recess in the end of an endwise movable rod against which the elbow-lever may 130 operate, which is a common construction (except, of course, the lever) in this class of hand-pieces. Other changes, of course, may be made without departing from my invention.

I do not deem it necessary, however, to recite in detail all the changes that might be made, as many of them will be obvious to constructors of dental machinery and tools of a kindred nature. In Fig. 7, however, I have shown a modification, in which the casing-sections, when closed or brought together, operate the elbow-lever by means of a wedging or camming surface instead of operating the lever to lock a tool in the spindle by separating said sections, as in the example first described.

Without elaborating the simplicity and effectiveness of my improved hand-piece, its durability, or its capacity for taking up or compensating for wear, or its ease and rapidity of operation, I will state that I claim herein as of my invention—

1. In combination with the casing of a dental-engine hand-piece, a spindle fitted to rotate in said casing having a journal tapered at different angles, substantially as described.

2. The combination of a spindle fitted to rotate in a hand-piece casing, a tool-locking device carried by said spindle, and connections between said tool-locking device and telescoping sections of said casing, substantially as described.

3. The combination of a spindle fitted to rotate in bearings, an endwise-movable tool-locking clamp carried by said spindle, and a rocking lever to operate said tool-locking clamp, substantially as described.

4. The combination of a spindle fitted to rotate in bearings in a casing, an endwise-movable tool-locking clamp carried by said spindle, a rocking lever to operate said tool-locking clamp, and movable sections of said casing to operate said lever, substantially as described.

40 5. The combination of a spindle fitted to rotate in bearings, a tool-locking device carried by said spindle, a rocking lever to operate said tool-locking device, and a wedge or incline to operate said lever, substantially as described.

6. The combination of the tool-lock-operating lever with the wedge or incline to operate said lever, having a notched or serrated surface, substantially as described.

7. The sectional split clamp tool-locking device, consisting of a front section having an externally-tapered or coned front end, and an internally-tapered mouth or socket at the opposite end, with a rear section having its front end coned or tapered to fit the coned mouth or socket of said front section, substantially as described.

8. In combination, with an endwise-movable clamp-locking device, a headed pin, fitted by its shank in said device and adapted to receive the pressure which closes the jaws of the clamp-lock, substantially as described.

9. The combination of a spindle fitted to rotate in bearings in a casing, but locked from independent endwise movement therein, a tool-locking device carried by said spindle, a driving-shaft also fitted to rotate in said casing and locked from independent endwise movement therein, a telescoping connection between the respective sections of said casing in which the spindle and shaft are mounted, and a connection between said shaft and said tool-locking device, whereby the reciprocation or telescoping of the casing-sections operate said tool-lock, substantially as described.

45 10. The casing of a dental-engine hand-piece having telescoping sections, one provided with a spline or feather, and the other with a groove to receive said spline or feather, substantially as described, whereby the casing-sections may be telescoped in a right line, but cannot turn relatively to each other.

In testimony whereof I have hereunto subscribed my name this 24th day of September, A. D. 1883.

ARTHUR W. BROWNE.
